POMPON MACHINE

Holger L. Lawson and Joseph Stampfli, Montreal,
Quebec, Canada, assignors to Hofmann &
Leavy, Inc., New York, N. Y., a corporation of
New York

Application July 8, 1935, Serial No. 30,292

5 Claims. (Cl. 28—2)

- The present invention relates to a machine for producing pompons and the like, and is a continuation in part of our United States application Ser. No. 714,578 filed March 8, 1934.
- 5 An object of the invention is the provision of a pompon forming machine which is completely automatic in operation.
- A further object of the invention is the provision of a pompon machine which is rapid in 10 operation and forms well constructed uniform products.
- Another object of the invention is the provision of a pompon machine designed so as to produce pompons of variable size.
- 15 A still further object of the invention is the provision of a pompon machine constructed so as to apply several windings of binding material to form a tightly bound tuft.
- Still another object of the invention is the 20 provision of a pompon machine which will accurately sever the pompon forming material so as to eliminate the necessity of separately trimming the pompons.
- Still another object of the invention is the 25 provision of a pompon producing machine of the above character which is relatively small, compact and durable in construction and reliable in operation.
- Other objects and advantages of the invention 30 will become apparent as the description progresses.
- In the accompanying drawings forming a part of this specification and in which like reference characters are employed to designate corresponding parts throughout the same:
- Figure 1 is a plan view of the assembled machine,
- Figure 2 is a side elevational view of the same,
- Figure 3 is a vertical longitudinal section on 40 the line 3—3 of Figure 1,
- Figure 4 is a longitudinal section through the pompon advancing mechanism,
- Figure 5 is a transverse section on line 5—5 of Figure 1,
- 45 Figure 6 is a fragmentary transverse section on line 6—6 of Figure 2,
- Figure 7 is a fragmentary section on the line 7—7 of Figure 2,
- 50 Figure 8 is a similar view showing the mechanism in a different position,
- Figure 9 is a section on the line 9—9 of Figure 7,
- Figure 10 is a transverse section on line 10—10 55 of Figure 1,
- Figure 11 is a similar view showing the mechanism in a different position,
- Figure 12 is a similar view showing the mechanism in still another position,
- Figure 13 is a view similar to Figure 12 with 5 part of the mechanism removed,
- Figure 14 is a similar view showing the mechanism in an altered position,
- Figure 15 is a top plan view of the same,
- Figure 16 is a section on the line 16—16 of 10 Figure 15,
- Figure 17 is a similar view with the mechanism in changed position,
- Figure 18 is a similar view in another position,
- Figure 19 is a similar view in still another position,
- Figure 20 is an enlarged fragmentary section on the line 20—20 of Figure 12,
- Figure 21 is a top plan view of the same,
- Figure 22 is a similar view showing the mechanism in another position,
- Figure 23 is a section on the line 23—23 of 15 Figure 10,
- Figure 24 is a sectional view taken on line 24—24 of Figure 10,
- Figure 25 is an enlarged fragmentary view of 20 the same,
- Figure 26 is a sectional view taken on line 26—26 of Figure 1,
- Figure 27 is a similar view showing the mechanism in another position,
- Figure 28 is a fragmentary view of the same 30 in a changed position,
- Figure 29 is a sectional view taken on line 29—29 of Figure 1,
- Figure 30 is a similar view showing the mechanism in another position,
- Figure 31 is a section through the bobbin structure, and
- Figure 32 is a section taken on the line 32—32 35 of Figure 24.
- Referring to the drawings, wherein for the purpose of illustration is shown a preferred embodiment of the invention, 40 designates the base of the machine which is in the form of an elongated 45 rectangular metallic plate. Journalled transversely on the base plate 40 adjacent what constitutes the forward end is a drive shaft 41 having fixed upon an extending end portion a clutch disc 42. Adjacent the disc 42 the drive shaft carries a slidably clutch sleeve 43 having rotatably mounted thereon an exteriorly grooved clutch wheel 44 engageable with the face of the clutch disc 42. The sleeve 43 is yieldingly urged to bring the wheel 44 into frictional contact with the disc 50 55

42 by means of a coiled compression spring 45 and is operable to disengage the clutch by means of an angular lever 46 pivotally supported upon an arcuate bracket 47. One arm of the lever 46 is 5 formed with a fork 48 provided with pins engaging the sleeve 43 while the opposed arm carries a plate cam 49 pivoted thereon and adjustable by means of an actuating lever 50.

Journalled longitudinally on the base plate 40 10 above and at right angles to the drive shaft 41 is a cam shaft 52 having a worm wheel 53 fixed on the forward end in mesh with a worm 54 on the drive shaft 41. To one side of the worm wheel 53 15 is secured a segmental cam 55 co-operatively engageable with the cam 49 to disengage the power driven pulley wheel 44 from the drive shaft clutch disc 42.

In a bearing block 57 on the base is journalled a drum 58 formed with annular grooves at the 20 intermediate portion and at the front end. In the front groove is rotatably fitted a helical gear 59 provided at one side with an annular boss in which is formed an annular groove 60 carrying a compression spring 61 therein. The gear 59 is in 25 mesh with a helical gear 62 on the main drive shaft 41, the drive mechanism being designed so that the gear 59 will complete nine revolutions during twenty-seven revolutions of the drive shaft 41 and one revolution of the cam shaft 52. 30 Fitted concentrically within and rigidly secured to the drum 58 is a lining tube 63 provided at the forward end with a knurled flange 64.

In a groove in the drum 58 is mounted an axially slidale clutch pin 73 yieldingly urged forwardly by a coiled spring so that the forward end will enter the groove 60 and engage the spring 61 of the helical gear 59 to cause rotation of the drum with the gear. At its intermediate portion the clutch pin 73 is formed with a transverse 40 tapered groove engageable with the lower end of an actuating arm 74. The arm 74 forms part of an angular bracket 75 pivotally connected to the end portion of a lever 76 pivoted vertically on a pin 77. A tension spring 78 connected with the 45 outer end of the bracket 75 yieldingly forces the end of the lever and the arm 74 downwardly so that the lower end of the arm will engage the intermediate groove of the drum and the groove in the clutch pin 73 to retract the latter and disengage the drum from the actuating gear 59. 50 The clutch actuating arm 74 is raised to disengage the clutch pin at regular intervals through the medium of a cam 79 fixed on the cam shaft 52 and engaging a follower pin on the inner end of the lever 76.

On the rearward extension of the tube 63 is threadedly secured an annular concentric bobbin casing 66 having rotatably fitted therein a bobbin 67 carrying a supply of binding wire 68. A 60 resilient dished ring 69 disposed between the side wall of the casing and the side of the bobbin provides suitable friction for proper rotary movement of the bobbin relative to the casing during the unreeling of the binding wire, the wire being passed through a slot in the periphery of the casing between a pair of guide pins 70 and looped about a take-off stud 71 mounted at an angular position on the edge of the casing.

Within the rotary lining tube 63 is mounted a 70 stationary feeder tube 78' formed with a tapered feed bore and supported at the front end upon a standard 79'. At the forward end of the feeder tube is secured a flaring feed funnel 80. In the bore of a standard 81 is removably secured a feed 75 support tube 82 having its bore in alignment with

the bore of the main feeder tube 78' and spaced from the rear end of the latter to form a narrow winding gap therebetween. At the inner edge of the vertical standard 81 is mounted a vertically 5 slidable cutter bar 83 provided at the lower end with a cutting edge operable to sever the binding wire. The cutter 83 is connected to the outer end of an arm 84, attached to a lever 85, and is normally held in an elevated non-cutting position by a spring 86 attached to the end of the lever. A cam 87 engages a pin 88 on the lever to periodically slide the cutter 83 downwardly to sever the binding wire.

A transverse twister shaft 90 is rotatably journalled opposite the support tube 82 and carries 10 thereon a fixed clutch collar 91 formed with a reduced annular guide boss 92. In an aperture in the collar 91, shown to advantage at Figures 24 and 32, is slidably disposed a clutch pin 93 normally extended by a spring 94 to engage a locking aperture 95 in the hub of a spur gear 96 loose on the shaft. The outer face of the pin 93 is shaped to provide an oblique shoulder, shown to advantage at Figure 24, periodically engageable with a trip arm 97 operable to retract the 15 pin to disengage the clutch connection between the collar 91 and the gear 96. The trip arm 97 is secured to the forward end of a lever 98 fastened to a crank of a rocker 99 formed with a stem 100 held against an operating cam 101, illustrated at Figures 1 and 5. The forward end of the lever 98 is yieldingly urged to a clutch pin 20 retracting position against the boss 92 by a tension spring 102 attached to the lever and to a bracket 103 on the base. The clutch gear is in 25 mesh with an idle gear 104 having driving connection with a spur gear 105 on the main drive shaft 41. Thus, the gear 105 fixed on the drive shaft 41 continuously rotates the clutch gear 96, 30 the clutch being engaged to rotate the twister 40 shaft 90 when the trip arm 97 is held in a lowered position away from the boss 92 and the pin 93. The clutch is disengaged to stop rotation of the clutch collar 91 and the twister shaft 90 when the trip arm is raised against the boss 92 by the 45 action of the spring 102 and the position of the cam 101. In this upward position the pin 93 will strike the trip arm 97 and the oblique cam forming shoulder will cause the pin to slide to a clutch 50 releasing position.

On the intermediate portion of the shaft 90 is fitted an axially slidale sleeve 107 urged to a retracted position against a slide block 108 by means of a coiled compression spring 109. This sleeve 107 extends through the shaft bearing and is formed at the front end with a slot 110, while the intermediate part is slotted at diametrically opposed sides to clear a thrust pin 111 extended transversely through the shaft. The forward part of the twister shaft 90 is provided with a longitudinal slot 112 and shaped at the extremity to form a wire gripping jaw 113. A lever 114 pivotally supported in the slot 112 is provided at the rear end with an angular slot 115 and with a transversely elongated jaw 116, co-operable with the fixed jaw 113, at the forward extremity. A diametrically extending pin 117 carried by the forward part of the sleeve 107 projects through the slot 115 so that forward thrust movement of the sleeve will swing the lever 114 to move the jaw 116 to an open wire releasing position, while retracted movement of the sleeve by the action of the spring 109 will swing the movable jaw to a closed wire gripping position. Forward 60 movement of the jaw actuating sleeve is effected 65 70 75

through the medium of a vertical lever 118 carrying a laterally projecting pin 119 engaging a groove in the slide block 108. The lever 118 also carries a second laterally extending pin 120 engageable by a plate cam 121 to effect automatic operation of the twisting jaws. These jaws may also be manually opened by depressing the lever 118 through the medium of a finger lug 122 on the upper end thereof.

10 To the front of a support web 124 on the base is attached a vertical plate 125 formed at the top to provide a guide notch 126 and a vertical cutting edge 127. Adjacent the top of the plate is mounted a transversely slidable block 128 formed at the front with a depending lip 129 roughened at the outer face to form a wire gripping anvil. Above this block is mounted a complementary slidable block 130 formed with a depending relatively long jaw forming lip 131 overhanging the anvil lip 129. The block 128 is resiliently urged to a forwardly projected position by a spring 132, while the block 130 is connected to the end of an actuating lever 137 through the medium of a pin 134. A spring 135 yieldingly holds a follower lug 136 on a pivoted lever 137 against the edge of an actuating cam 138 operable to effect proper movement of the jaw 131.

20 Projecting laterally from the outer end of a lever 140, pivoted to the side of the web, is a stem 141 operable to depress the binding wire into twisting jaw engaging position. The inner end of the lever 140 is yieldingly pressed against a cam hub in the path of an actuating eccentric pin 142 by a tension spring 143 so that the stem carrying lever is periodically actuated to adjust an end of the binding wire.

25 A pair of cutting blades 145 and 146 formed with slotted cam plates 147 are pivotally supported in vertical position. Through the slots 30 of the cam plates 147 is extended a pin 148 secured upon a vertically supported lever 149 and engaging the edge of an actuating cam 150. A complementary cam 151 is mounted to actuate a follower pin 152, also secured to the lever 149, 35 so that the blades are periodically actuated to effect scissor movement to sever a portion of the bunch.

35 To a collar 154 fixed on one end of a rock shaft 155, journalled in an elevated bearing 156, is secured a fork 157 curved at the lower end so as to brace the pompon forming bunch during the cutting operation. To the same collar is secured an arm 158 adapted to strike the severed pompon and eject the same laterally of the machine. 40 Upon the opposite end of the rock shaft is secured a crank 159 having pivotally connected thereto one end of an actuating rod 160. The opposed end of the rod 160 connects with a follower pin 161 projecting laterally from a lever 162. A spring 163 fastened to the lever resiliently forces the follower pin 161 against the edge of a cam plate 164 formed so that the fork 157 and the ejecting arm 158 are periodically oscillated.

45 The pompon forming threads are advanced to cutting position by puller mechanism embodying a tubular shaft 166 slidably supported in longitudinal position in bearings 167 and 168 and provided with a slot 169 intermediate its ends. Within the shaft 166 is slidably fitted a rod 170 formed with an intermediate groove 171 and provided at the forward end with an enlarged head 172 carrying radial pivot pins 173. To these pins are connected the pivot brackets of a pair of complementary longitudinally disposed jaw levers 174 formed at the forward ends with a pair of co-

5 acting jaw plates 175. The rear ends of the levers 174 are pivotally connected with a flanged head 176 on the forward end of the shaft 166 by links 177. Intermediate the ends the jaw levers 174 carry studs 178 to which are fastened 5 a pair of tension springs 179 arranged rearwardly of the pivot pins 173 and tending to normally swing the jaws 175 to separated open position. Upon the rear end of the tubular shaft 166 is slidably fitted a socket 180 having threaded 10 connection with the end portion of the rod 170. A nut 181 locks the socket in adjusted position on the rod. A detent 182 is pivotally supported in the slot 169 of the shaft and is resiliently urged inwardly against the rod by spring means and is 15 operable to engage the groove in the rod to resiliently retain the latter in retracted position relative to the shaft.

To a block 184 secured on the shaft 166 is pivotally connected the outer forked end 185 of a 20 lever 186. A follower pin 187 carried by the lever engages the groove of an actuating cam 188 to suitably oscillate the shaft. Thus, when the shaft is moved to its extreme forward position the socket contacts with the shaft bearing 168 to 25 arrest movement of the rod 170 before the shaft 166 terminates its forward movement, causing the rod to assume a relatively retracted position so that the jaws 175 are swung to closed bunch gripping position and the detent 182 assumes an inward position engaging the groove 171 in the rod to secure the latter in jaw closing arrangement. The jaws are held in closed bunch gripping position during the rearward stroke of the shaft until the detent engages the rear shaft 30 bearing 167 and is automatically actuated thereby to release the rod, enabling the springs 179 to effect opening movement of the jaws.

35 The machine operates as follows:

A bunch of threads, that is a plurality of 40 strands of silk, rayon, wool or the like, is inserted into the bore of the feed tube 78 and the bore of the support tube 82, bridging the gap between these elements. As the cycle of operations commences the outer end of the binding wire a is 45 secured between the jaw 131 and the outer anvil face of the jaw 129. The bobbin casing is then rotated, in a direction shown by the arrow at Figure 15, winding the wire circumferentially a number of turns, in the present instance three, 50 about the bunch in the winding gap. As the last winding turn is nearing completion the jaw 131 opens to release the initially gripped end portion of the wire and to intercept another part of the wire. At this time, the stem 141 descends to 55 dispose the part a^2 to a lowered position, as shown at Figure 16, while the part a^3 moves under the jaw 131. The jaws 131 and 129 are then retracted, cutting part a^3 of the wire from the main body of the wire as it is moved against the cutting edge and securing the end of the main body again between the retaining jaws. The end portions a^2 and a^4 of the wire, Fig. 17, are then engaged by the projection of the opened rotating twisting jaw 116 and brought to proper position 60 between the jaws which close tightly on these ends and twist the same as they continue to rotate, effecting a suitable number of turns to fasten the wire, in the present instance about six turns. When the final twisting turn is completed, the cutter 83 is depressed from its normally elevated position to cut the twisted portion of the wire, the severed ends dropping from the twisted jaws and may be collected in a suitable container on the base. As will be noted at 65 70 75

Figures 11 and 12, the guide bores in the feed tube 78 and support tube 82 are formed eccentrically so that regardless of the diameter of the pompon forming bunch the length of the twist 5 will be approximately uniform.

Upon completion of the twisting operation the advancing jaws move forwardly and grip the rearwardly projecting portion of the bunch and advance the same a predetermined distance. The 10 scissor blades sever the bunch forwardly of the support tube forming a pompon tuft of predetermined length which, upon opening movement of the jaws, is struck by the ejecting arm 158 and thrown laterally from the machine into a suitable receiver.

Thus, it will be noted that the successive operations of binding the bunch at a predetermined point, advancing and severing the same at a predetermined distance from the advanced end and 20 ejecting the severed pompon are affected automatically and with great precision. The ejected pompons are consistently uniform in length and are cut by the scissor cutting mechanism so efficiently as to obviate the necessity of subsequent 25 trimming. As the machine is designed to produce a complete pompon for predetermined revolutions of the shafts, as for instance one pompon for each revolution of the cam shaft, the number of pompons produced in a given time may be 30 readily determined when the operating speed is known. Thus, if the cam shaft is driven at a rate of forty R. P. M., it is apparent that forty pompons will be produced during each minute of 35 operation, obviating the necessity of counting the completed pompons.

Having thus described our invention, we claim:

1. A pompon forming machine having in combination, a guide for a bunch of pompon forming threads, means for winding a binding element a 40 plurality of turns on the bunch, means for advancing the bound threads, means for cutting

the advanced bound threads to form pompons of uniform length, and means for automatically ejecting the severed pompons from the machine.

2. In a pompon forming machine, the combination of means for guiding a bunch of threads, 5 means for winding a binder about the bunch, means for twisting the binder, means for advancing the bound bunch, scissor blades operable to sever the advanced portion of the bunch to form the pompon, and a member movable to brace the bunch adjacent the blades during the bunch severing operation.

3. In a pompon forming machine, the combination of means for guiding a bunch of threads, 15 means for winding a binder about the bunch, means for twisting the binder, means for advancing the bound bunch, scissor blades operable to sever the advanced portion of the bunch to form the pompon, a member movable to brace the bunch adjacent the blades during the bunch 20 severing operation, and an ejecting member adapted to strike and eject the pompon upon completion of the severing operation.

4. In a pompon forming machine, a thread feeding guide, means for releasably gripping and 25 advancing the threads to a projected position, means for severing the projected threads, means adapted to support the projected threads during the severing operation and to throw the severed portion of the threads laterally with respect to 30 the guide.

5. In a pompon forming machine, a thread feeding guide, means for releasably gripping and advancing the threads to a projected position, 35 means for severing the projected threads, and means adapted to laterally eject the severed threads as they are released from the gripping means.

JOSEPH STAMPFLI.
HOLGER L. LAWSON.
